UNITED STATES PATENT OFFICE.

HARRY L. VAUGHAN, OF CHICAGO, ILLINOIS, ASSIGNOR TO CROWN THROAT & OPENER COMPANY, OF CHICAGO, ILLINOIS, A CORPORATION OF ILLINOIS.

DESIGN FOR A BOTTLE-OPENER.

44,945.

Specification for Design.

Patented Nov. 25, 1913.

Application filed October 8, 1913. Serial No. 794,174. Term of patent 7 years.

To all whom it may concern:

Be it known that I, HARRY L. VAUGHAN, a citizen of the United States, residing at Chicago, in the county of Cook, State of Illinois, have invented a new, original, and ornamental Design for Bottle-Openers, of which the following is a specification, reference being had to the accompanying drawing, forming a part thereof.

The figure is a plan view of a bottle opener showing my new design.

I claim:

The ornamental design for a bottle opener, as shown.

HARRY L. VAUGHAN.

Witnesses:

SADIE M. RYAN,
JAMES R. OFFIELD.
